(57) **CLAIM**

The ornamental design for a beam, as shown and described.

DESCRIPTION

FIG. 1 is a top left perspective view of the beam;

FIG. 2 is a top right perspective view of the beam of FIG. 1;

FIG. 3 is a bottom left perspective view of the beam of FIG. 1;

FIG. 4 is a bottom right perspective view of the beam of FIG. 1;

FIG. 5 is a front elevation view of the beam of FIG. 1;

FIG. 6 is a rear elevation view of the beam of FIG. 1;

FIG. 7 is a left elevation view of the beam of FIG. 1;

FIG. 8 is a right elevation view of the beam of FIG. 1;

FIG. 9 is a top plan view of the beam of FIG. 1; and,

FIG. 10 is a bottom plan view of the beam of FIG. 1.

The drawings contain symbolic break lines in FIGS. 1-4 and 7-10. The break lines and the portions of the article between the break lines forms no part of the claimed design.

1 Claim, 9 Drawing Sheets
